SwedenApplication March 2, 1936, Serial No. 66,710
In Sweden February 12, 1935

5 Claims. (Cl. 116—147)

A well-known type of sirens for signaling purposes bases its action upon the use of a fluid under pressure, usually compressed air generated by means of a rotary compressor wheel or delivered from a separate reservoir, the air being discharged from a chamber at certain determined intervals into the open air through a sound aperture or apertures from which there may lead horns for controlling the direction or 10 directions of the sound. In sirens of this type, the sound is produced by variations of the pressure in said chamber obtained as a result of the alternate opening and closing of said aperture or apertures. If horns are used, they not 15 only guide and direct the sound vibrations but act also as discharge passages for the exhaust fluid, thereby interfering with the formation of the sound vibrations. In another well-known type of sirens, the sound producer comprises a 20 diaphragm vibrated either by means of an electromagnetic force or by the action of compressed air. In the last-mentioned case the diaphragm is situated in a sound chamber to which leads a pipe for the compressed air in such a way as 25 to have its mouth opposite the diaphragm. The sound chamber is provided with a horn, and the diaphragm acts as a valve for said pipe in order to periodically discharge a quantity of compressed air through the horn, thereby giving 30 rise to a natural vibration therein. In this type of sirens the force, whether it is produced by an electromagnet or by compressed air, may only act upon a restricted portion of the diaphragm near its centre, so that only diaphragms of rather 35 small dimensions may be used. In case of larger diaphragms of substantial mass, the whole diaphragm cannot take part in the vibration as a result of such a concentrated action, particularly not at high frequencies, so that the vibration 40 will be limited to the central portion of the diaphragm. As a strong sound requires a large diaphragm, the range of use of sirens of this type will be correspondingly limited. It is further to be noted that in sirens having a diaphragm operated by means of compressed air, the horn acts as an outlet for the exhaust air 45 and will, as a result, cause such an interference with the sound vibrations as that already referred to hereinbefore in connection with the 50 description of the first stated type.

The object of this invention is to provide a siren by which the above stated drawbacks are overcome, and which presents, in addition, several great advantages.

55 The invention relates to that type of sirens in

which a diaphragm is provided as a sound producing member in a chamber formed with a constantly open sound aperture or apertures on one side of the diaphragm. The principal characteristic feature of the invention involves that 5 the vibrations of the diaphragm are produced by means of a fluid under pressure, that is to say, a pressure above or below atmospheric, which is intermittently admitted to the surface of the diaphragm remote from said sound aperture or 10 apertures under the control of a valve mechanism, the operation of which is independent of the vibrations of the diaphragm.

In the accompanying drawing an embodiment 15 of the invention is shown in axial section in the single figure.

In the embodiment shown the numeral 1 indicates a, preferably circular, diaphragm which is inserted as an intermediate wall in a chamber formed between a bottom piece 2 and a cover 20 3 both of which are formed with peripheral flanges, between which the circumferential portion of the diaphragm is clamped. Said flanges are held together by screws 4 extending through suitable washers 5 of a thickness equal to that 25 of the diaphragm, or somewhat thicker, there being left a space between the inner periphery of the annular washer and the outer periphery of the diaphragm sufficient to permit a radial expansion of the diaphragm, which is necessary, 30 for instance, if the diaphragm, when in operation, is heated by a hot gas used as an operating fluid. In the embodiment shown the bottom piece 2 represents at the same time an end wall 35 of a pressure chamber 6 adapted to receive a compressed gas which may be admitted thereto by a pipe 7 or the like, leading, for instance, from a rotary compressor located outside said chamber. Extending centrally through the chamber 6 is a rotatable shaft 8 projecting into 40 the space 9 between the end wall 2 and the diaphragm 1 and carrying in said space a disk shaped slide valve 10 having two sets of apertures 11, 12, concentrically surrounding the shaft 8. The apertures 11 are situated above a 45 set of apertures 13 leading to the pressure chamber 6 and, similarly, the apertures 12 are situated above a set of apertures 16 leading to the atmosphere.

The cover 3 is provided with a central port 50 from which projects a horn 15.

The shaft 8 is adapted to be rotated at a varying number of revolutions, as for instance, by an electric motor or the like. The apertures 11, 12 of the slide valve 10 and the apertures 13, 14 of the 55

end wall 2 are so related with respect to each other that upon the rotation of shaft 8, the space 9 between the diaphragm 1 and the slide valve 10 will be alternately communicated with the pressure chamber 6 and the atmosphere. As a result of this operation, the diaphragm will be alternately subjected to a pressure above atmospheric and to the atmospheric pressure and will, consequently, vibrate at a frequency determined by the speed of rotation of the shaft 8 and the number of apertures. When the diaphragm is pressed upwards under the action of a pressure above atmospheric, it will act as a piston in the space 16 between the diaphragm and the cover 3. The height of said space should be so determined that the principal part of the air in the chamber 16 will be discharged into the horn as a result of the upward movement of the diaphragm. Due to the increase of pressure to which the air in the horn is now subjected, immediately followed by a reduction of pressure, as soon as the apertures 14 are uncovered and the pressure above atmospheric hitherto acting on the lower side of the diaphragm ceases, allowing the diaphragm to return to its original position by its inherent elasticity, a sound vibration will be produced. It is evident that in this operation, the horn need only act to transmit the sound vibration, but does not act as an outlet pipe for the exhaust fluid, because the diaphragm closes the horn with relation to the pressure chamber 6. At each vibration the quantity of driving fluid that may be contained in the space 9 is allowed to escape, and to each individual tone there corresponds a definite number of such quantities. In order to avoid undue losses of driving fluid, it is thus advisable to make the volume of the space 9 as small as possible by limiting the height of said space to what is strictly necessary for allowing the return vibration of the diaphragm. This is due to the fact that the diaphragm also performs a fully developed negative vibration, below its central position.

The apertures formed in the slide valve 10 and the rigid end wall 2, by which the frequency is determined, act also to determine to a certain extent the curve representing the vibrations of the diaphragm. It is thus possible, by suitably shaping these apertures, to obtain an adequate shape of this curve, allowing the apertures to regulate the admission and discharge of the driving fluid and thus also the variations of pressure upon the diaphragm in agreement with each angular variation during the rotation of the slide valve in a predetermined manner. If desired, provisions may be made to allow the driving fluid to expand in a certain degree in the space 9 below the diaphragm before discharged to the atmosphere.

It has been stated hereinbefore that the use of a fluid under pressure for the operation of the diaphragm in the manner described involves that the power will act simultaneously upon the whole diaphragm, as distinguished, for instance, from the action of an electromagnetic or mechanical force which is restricted to a smaller area. As the mass of a gaseous fluid under pressure is very small and the outlet velocity of such a fluid through the slide valve apertures of the siren increases with increasing pressure, it is easy to raise the frequency very high and to vary the force acting upon the diaphragm.

Variations relating to the construction may be

made in many ways without departing from the principle of the invention.

What I claim is:—

1. A siren, comprising means forming a chamber, a diaphragm inserted as a sound producing member in said chamber so as to divide it into two spaces, said chamber having a constantly open sound emission port opening to one of said spaces, said chamber also having separate admission and discharge apertures opening to the other of said spaces for a driving fluid, a rotary slide valve having apertures to control both said admission and said discharge apertures so as to alternately admit and discharge driving fluid to and from said other space. 15

2. A siren, comprising means forming a sound chamber having two oppositely disposed walls, one of said walls having a constantly open sound port, a diaphragm inserted in said chamber so as to divide it into two separate spaces, each facing a separate one of said walls, means forming a driving fluid chamber situated outside the other one of said walls, said other wall having a set of apertures connecting the driving fluid chamber with the space facing said other wall, said other wall having another set of apertures leading from the space between the diaphragm and the said other wall to the atmosphere, and a rotary slide valve having apertures therein inserted in said last-mentioned space to control said two sets of 30 apertures in alternation.

3. A siren, comprising two end walls and a peripheral wall forming a sound chamber, one of said end walls having a constantly open sound port, a diaphragm mounted in said chamber 35 clamped loosely at its periphery in said peripheral wall to allow of expansion thereof, said diaphragm dividing the sound chamber into two separate spaces, each facing a separate one of the end walls, means forming a driving fluid chamber outside the other end wall, said other end wall having a set of apertures, communicating the driving fluid chamber with the space adjacent said other wall, said other wall being provided with another set of apertures leading from the space between the diaphragm and the said other wall to the atmosphere, and a rotary slide valve having apertures therein inserted in said last-mentioned space to control said two sets of apertures in alternation. 50

4. A siren having, in combination, means forming a sound chamber said means including two end walls and a peripheral wall, one of said end walls having a sound emission port and the other end wall having inlet and outlet apertures for a 55 driving fluid, a diaphragm inserted in said peripheral wall so as to divide the sound chamber into two separate spaces each facing an individual one of said end walls, both of said spaces having a height perpendicular to the diaphragm 60 which is substantially only as great as is necessary to permit the vibrations of the diaphragm and a rotary valve having apertures therein for controlling said inlet and outlet apertures mounted adjacent said other end wall. 65

5. A siren as claimed in claim 1, in which the discharge aperture of the other chamber is situated near its periphery in order to allow the fluid to be discharged, in part, by the action of centrifugal force. 70
